UNITED STATES PATENT OFFICE.

JEDDY D. NIXON AND MARGIA MANNING, OF HOUSTON, TEXAS.

BACK-PRESSURE VALVE.

Application filed August 2, 1926. Serial No. 126,452.

This invention relates to new and useful improvements in a back pressure valve.

One object of the invention is to provide a valve of the character described, adapted 5 to be mounted in a set shoe and specially designed to be associated with a wash pipe used for washing the screen set in a well bore, and which is effective to cause the return of the washing fluid delivered through 10 said wash pipe either up around the outside or within the screen, to which said set shoe is attached, as desired.

Another object of the invention is to provide a valve of the character described of 15 such construction that it will not become readily worn away and caused to leak by the gritty fluid to which it is subjected.

A further feature of the invention is to provide a back pressure valve whose casing 20 25 is provided with means for anchoring the casing during the manipulation of the valve.

With the above and other objects in view this invention has particular relation to certain novel features of construction, operation 30 35 and arrangement of parts, an example of which is given in this specification and illustrated in the accompanying drawings, wherein:—

Figure 1 shows a vertical sectional view 30 showing the valve in position for washing the outside of the screen.

Figure 2 shows a cross sectional view taken on the line 2—2 of Figure 1.

Figure 3 shows a cross sectional view 35 taken on the line 3—3 of Figure 1.

Figure 4 shows a side elevation of the valve in position for washing the inside of the screen and shown partly in section, and

Figure 5 shows a bottom end view of the 40 device.

Referring now more particularly to the drawings, wherein like numerals of reference designate similar parts in each of the figures the numeral 1 designates a screen, 45 adapted to be set in a well bore. Attached to the lower end of this screen is a tubular set shoe 2, the lower end of which carries the tubular guide point 3, said shoe and guide point forming a valve casing. The 50 lower end of this guide point is contracted and provided with a restricted discharge port 4, and said contracted end has the radiating fins 5 adapted to engage the formation at the bottom of the bore to anchor said 55 valve casing against turning for a purpose to be hereinafter explained.

The upper end of the guide point has the conventional, downwardly opening back pressure valve 6, therein.

Threaded into the upper end of the set 60 shoe 2 there is an annular anchor 7 having a central tapped hole 8 whose lower end is flared forming a smooth seat 9, and threaded through this anchor there is a tubular valve 10 whose shank is externally threaded. The 65 lower end of the valve 10 is closed by a cap 11 whose upper end is beveled, as at 12, and thus conformed to the contour of and adapted to seat against the seat 9.

The upper end of the valve has an ex- 70 ternal annular shoulder 13, adapted to abut against the anchor 7 and above said shoulder the valve 10 has a socket 14, polygonal in cross section, and whose upper end is flared, as at 15. The shank of said valve 75 10 has the radial ports 16 intermediate its ends.

In operation, when the screen 1 is set in the bore and it is desired to wash the same a wash pipe 17 is lowered and its lower end 80 85 18 polygonal in cross section is seated in the socket 14, as shown in Figure 4. If it be desired to wash the outside of the screen the wash pipe 17 may be turned to screw the valve 10 downwardly through the anchor 7 85 so that the discharge ports 16 will be beneath said anchor, as shown in Figure 1. Water may now be forced, under pressure, down through the wash pipe and out through said ports 16 and it will lift the valve 6 and pass 90 out at the port 4 and up around the outside of the screen. If it be desired to wash the inside of the screen the valve 10 may be screwed upwardly by the wash pipe, through said anchor 7 to carry the ports 16 above 95 the anchor and to seat the upper end of the cap 11 against the seat 9, as shown in Figure 4. Water under pressure, may now be forced down through said wash pipe and out through the ports 16 and up inside of 100 the screen. The fins 5 will anchor the valve casing against turning during the manipulation of the valve 10.

While the screen is being set and washed the valve 6 will prevent gas, oil or earth 105 formation from entering the lower end of and passing up into the screen.

After the screen is washed and the well is ready to produce oil the wash pipe is withdrawn and the valve 10 is maintained in its 110 last mentioned position, as shown in Figure 4, and thus effectively prevents oil or for-

ign matter from entering the lower end of the screen but forces the oil to enter through the screening surface of the screen, by which detritus and foreign matter is excluded.

5. What we claim is:—

1. A device of the character described including a tubular valve casing, a transverse partition therein forming an anchor, a tubular valve having a discharge port and 10 threaded through said anchor so that said port may be shifted from one to the other side of said partition.

2. A device of the character described including a tubular set shoe, forming a valve 15 casing, an anchor therein, a tubular valve secured to said anchor and having an inlet fluid conduit and a discharge port, operative connections between the anchor and valve whereby the valve may be adjusted to permit 20 the discharge of fluid through said port on either side of the anchor.

3. A device of the character described including a tubular set shoe, forming a valve 25 casing, a partition therein, a tubular valve having an inlet fluid conduit and a discharge port, operative connections between the partition and valve whereby the valve may be adjusted to permit the discharge of fluid through 30 said port on either side of the partition, spaced abutments on said valve adapted to alternatively abut against and form a close fitting joint with said partition.

4. A device of the character described including a tubular set shoe, adapted to be 35 attached to a well screen, a transverse partition therein, forming an anchor, a tubular valve whose lower end is closed and whose upper end has a water channel therethrough 40 which terminates in a lateral discharge port, said valve being threaded through said anchor, to permit the adjustment of the valve to carry said port above or beneath said anchor.

45. 5. A device of the character described including a tubular set shoe, adapted to be attached to a well screen, a transverse partition therein, forming an anchor, a tubular valve whose lower end is closed and whose 50 upper end has a water channel downwardly therethrough which terminates in a lateral discharge port, said valve being threaded

through said anchor forming an adjustable connection to permit said port to be adjusted into position above or beneath the anchor, 55 an annular outside abutment on said valve beneath said port adapted to abut against said anchor.

6. The combination with a tubular set shoe having a transverse partition therein, forming an anchor, of a tubular valve 60 threaded through said anchor and having a channel leading downwardly therethrough and terminating in a lateral discharge port, a wash pipe whose lower end is operatively 65 connected with but detachable from the upper end of said valve through which said valve may be adjusted relative to said anchor to locate said port on either side thereof.

7. In a device of the character described 70 an anchor, a valve threaded through the anchor, said valve having a channel leading through the valve from one end and terminating in a lateral port, spaced abutments on said valve adapted to alternatively abut 75 against and form a close fitting joint with said anchor.

8. In a device of the character described, an anchor, a valve threaded through the anchor, said valve having a channel leading 80 through the valve from one end and terminating in a lateral port, said valve being adjustable relative to the anchor to locate said port on either side of the anchor.

9. The combination with a well screen, of 85 a set shoe attached to the lower end thereof, a wash pipe within the screen and means through which fluid conducted downwardly through the wash pipe may be returned up inside and outside of said screen alternatively, said means including an anchor, a valve threaded through said anchor and having a channel leading through the valve from one end and terminating in a lateral port, the lower end of the wash pipe and the 90 upper end of the valve being formed to permit their operative connection whereby the valve may be adjusted, from said pipe, to locate said port on either side of the anchor.

In testimony whereof we have signed our 100 names to this specification.

JEDDY D. NIXON.
MARGIA MANNING.
